Friends' Meeting of Newmarket Union

1

881DX Letter-Patent

The Solemnity referred to in these Letters-Patent and making part of the same containing a description in the words of the said Friends' Meeting Union of this improvement in an apparatus for printing called Newmarket Simplified Printing apparatus.

Be it known that Friends' Meeting of Newmarket Townships, Province of
Ontario and State of Ohio, have made an improvement in the method and
construction of an apparatus for printing, called Newmarket Simplified Printing
apparatus, which is described as follows. Part 1. A frame or case
upon which supports are resting the different parts. The platform or table on
which the types are placed. Three press rollers connected together at their
ends in a triangular relation to each other, one to pass over the types,
called the impression roller, supported at each end by a lateral rail,
way and two counter pressure rollers, working up against similar rail
ways upon which the type table rests, cleamps and guides for making the
register; Inkling apparatus, consisting of a chest or box containing the inks
reservoir, distributing rollers, ink rollers, with blocks in which they are
suspended. Said blocks regulating the height of the ink rollers by nuts
and screws. A trough for holding water to keep the rollers moist. The
frame (a) in the annexed drawing is made rectangular, of any convenient
size adapted to any kind of work for which it is intended. On the upper
side is a plain horizontal surface made of iron, stone, wood, or any other
suitable material, and it may be covered with a thin coating of shell-lac
and sand, or shell-lac and iron filings, or when made of wood the under
or first part of the coating may consist of glue and sand, and the upper
or finishing coat of shell-lac and iron filings. The form of types is placed
upon this surface above this table and resting on the sides thereof on another
frame (b) called the upper rail-way between which and the table is put
some elastic substance, such as hot cloth, metal springs, or granules
etc, for keeping the press rollers always at the desired height, being

This is made in all to allow the impression roller to approach near enough to the type to give the impression, but never falling below the level of the surface. The rail ways may be made of wood alone, or wood with metallic rods (c) fastened in them after sides, the impression roller having a groove at each end on which the iron rods work, and a pin which the impression roller moves back and forward; the impression roller (d) is made of wood ^{or metal} and turned true, and of any convenient diameter, from $2\frac{1}{2}$ to five inches being covered with cloth, or other elastic substance, the cloth must be closed by a fine drawn seam to preserve an equal surface, the cloth being covered lastly with paper, to be changed when desired. The pressure upon the types is regulated by the screw (h) acting upon the metallic screw (i) over the qualities of the impression roller being counteracted by the two under rollers (k), pressing up against the under surface of the under railways (l) said rail ways may be of wood, or metal or both. The under or counter pressure rollers may be made of wood with or without metallic ends, having grooves or flanges to keep them in back. The three combined rolling on kept square or at right angles, with the type table by means of rods (m) or rackets & pins upon the under rollers. The under rollers are placed at a suitable distance apart so that when the combination of rollers is moved the motion will be steady and the pressure uniform. To keep the paper smooth and to prevent its running before the impression roller, a bar (n) is placed over the impression roller, over which the paper is thrown. When this friction is not sufficient to prevent the paper from wrinkling, the roller (o) is thrown on to the Y (p) to add to the friction by the whole or part of its weight, this being modified by the screw of the Y together with the elastic clothings of said roller; on the paper is thrown over the roller, when the least friction is desired. The repeating clamp (q) consists of two principal hinged together and made of el. pleasure, having points, fixed at convenient distances in one side and corresponding holes in the other. There are other points in the furniture which is looked up with the same and placed at any convenient distance from the types and corresponding holes in said clamp, fitting upon the points in the furniture which

bring the paper (2) when clamped in the right position to be printed, and furniture having also shottz to guide the his edge of the clamps, who press. S is a square board having a rabbit (6) at one end at right angles with its sides. The clamps being fixed upon a support the shoulder of the rabbit receive one end of the paper when it is laid on the board, the edge of the sheet corresponding with the edge of the board, the clamp (3), being shut, close the paper in a proper position to be printed. The pin in the clamp for perforating the paper, by which holds the second edge of the sheet is required. In a dressing sheet of different widths a movable pin (12) is used against which the end of the clamp is placed so as to make the paper when clamped, correspond with the form. The inking apparatus (V.) may be double or single one or two to each press. The double inker is constituted as follows, the typable (1) resting at the end upon friction roller (6) which are caused to run upon the rods of the tailways. It consists of a box (X) a receptacle containing two ink rollers (Y) suspended by hooks, and their height regulated by the screw and nut (Z) at the top of said hooks. Above the ink roller is a distributing roller (1) which receives ink from the cloth (2) in the bottom of the ink reservoir (3) and is then dropped down upon the ink roller, and turned by a crank (4) having also a lateral motion, which motion distributes the ink upon the ink roller, which being done, the distributor is lifted from the ink roller and suspended between them and the ink reservoir by means of turning the bar (5) so that the short pins (6) stand vertically. Then more ink is taken from the bar ^{the reservoir} turned further round, and the long pins (7) from the distributor against the reservoir and keep it there if desired.

In printing a small form the little transverse roller (8) is worked upon the distributor to carry the ink from the cloth to the desired place. Above the distributor is the ink reservoir having a top (9) and fastened with a bolt stopped with a screw (10). The object of the no light top is to prevent the ink from falling when not in use, and that of the screw stopper is to let air in when the ink is required. The bottom of the ink reservoir (11) is movable at pleasure having attached to it a trough (12) made of lead or other metal not subject to ^{cor} _{dis}.

by hand. This having the ink roller and the box rolling over it. Keeping the roller, round the sides of the box there are steps (13) through which the handles of the transverse rollers (14) of rotate. These being stopped with stops, render the box, while not at work, unworkable to start, and keep the moisture within the box. The simple unworkable box ink roller the work being taken from the box by the little transverse roller which is then dropped down upon the ink roller, and worked from end to end of it, giving the handles of the transverse roller an oblique motion by which the ink roller is turned. The object of this invention is to simplify and shorten the printing place so as to adapt it to the condition and capacity of private citizens. It may however be used to advantage by professional printing. When used by private citizens, the press, printing apparatus, type cases, and all the implements necessary for printing are enclosed (if desired) in a piece of furniture such as a secretary (14) dining table, chest of drawers, or counting house desk. These contained with the secretary or similar piece of furniture the end are closed with falling doors (15) the type table (16) and cases (17), being concealed underneath. The type table when drawn out is supported at the outer end by a moveable standard (18), the other end remaining in or resting on the piece of furniture to which steps are affixed to slope it at the proper place. But when shut up the roller printing apparatus may be deposited in one of the drawers (19). When the types are to be handled by those who are unaccustomed to them use, I propose that the ~~inches~~ in ^{feet} spaces, quadrangular, intended to measure, & should be made to correspond with those in the letters, & as to admit a thread running them, consisting each comprising sticks full together, so that they can be handled while dry and clean without dislodging them, and without that tact and skill which result from long experience. Mode of manufacture; the type table when made of iron, may be covered with a hard coating of shell lac and varnishing, and fitting to shell lac and stand, thus having the bed fastened permanently upon the under railings which are finished ready for printing, put a thick coat of shell lac dissolved in good alcohol over the surface of the bed, then there on follow varnishing, and when the shell lac has set brush off the loose varnish, and what sticks constitute a line of frame work for the coat. Put on the combination of press rolling (21)

making the under roller (H) take up against the under railways, then
 bring the top roller so that when worked back and forth it will roll down
 the casting to a surface corresponding exactly to the surface of the top roller
 and the two railways. Then each and the process is to be repeated till the
 top roller touches at all points. Then another coat of shell lac is spread
 on with a straight edge, and iron filings or dry sand is immediately sifted
 over the surface, when they become dry it is cleaned down with sand
 stone, and the dust made by cleaning is used in the afterwards instead
 of sand, or mixed with iron filings or fine borings, and this process of
 cleaning and sifting is repeated till the surface is sufficiently even.
 Then the roller is put on the railways at top and bottom as if for print-
 ing and a block of wood is cut out so as to fit the diameter of the impression
 roller, and slipped on it and reaching down to the surface to be scoured,
 adjust both ends of the impression roller (d) precisely at the same distance
 from the under surface of the under railway, then three dry sand are on
 the surface and move the roller back and forth, and the block alternately
 along the whole width of the bed, thus grinding the surface to correspond
 at all points with the impression roller, now the surface of the impression
 roller as a guide to the grinding block, when the bed is made of
wood there are mouldings (H) all round projecting above the wood founda-
 tion, take a gauge or writing tool with two points to answer to the
 bed under roller, place the bearing points up against the under railway and
 and strike the upper surface of said moulding down to the desired height, so
 that using the scribed edge as a guide for the thickness of the casting it will
 be from an eighth to a quarter of an inch thick. Then take warm glue and
 sand about the consistency of cream, or as thick as it will spread, and
 having the wooden surface previously heated at or above the same temperature,
 spread on the coat of glue and sand, with a straight edge or spread-
 ing box, using the scribed edges of the projecting moulding as gauges or set-
 ting points for the straight edge or box and before the glue cools sift a much
 fine sand onto its surface as it will receive. When dry brush off the loose
 sand and spread to finish with coats of shell lac and iron filings as
 before directed. To avoid the necessity of scouring the wooden bed which is
 done

to prevent blunting the glue and sand may be put on in two coats, the blunting of the first being that of no consequence; in which case dry sand is not sifted into the surface of the first coat, in this last case the straight edge of box is notched at the ends where it bears upon the mouldings, so that the first coat shall constitute but about half of the thickness of the covering, the next coat is put on in the notches in the spreading tool which makes the surface flush with the top of the mouldings. The top surfaces of said mouldings are used throughout the process of spreading the upper coats of dressed shell lac. The object of which is that the surface of the type can be easily made to correspond with the surface of the under railings, upon which correspondence the perfection of the impression depends. The roller moulds are made by dipping a polished mandible into melted metal such as lead and antimony equal parts, or greater, a coat immediately chills around the mandible, which is then stretched with gentle blows of a hammer, and being thus disengaged the mandible is forced out by placing a wooden plug against the end and striking a heavy blow with a large hammer. Adding a tin bottom to this tube it is ready for use after putting to it the usual top. The troughs in the ink boxes are made by dipping a mandible part way into the melted metal in a horizontal position. The coat that chills forms the trough complete, if the trough be so long as to settle in the middle upon drawing out the metal the middle is sustained by a hook in the hand of a second person.

Mode of Operation. The types being placed on the table or platform locked up in a case in the usual manner, with the registering pieces of furniture placed at a proper distance from the form of types. The rollers of the inking apparatus having been supplied with ink are passed over the form by moving the apparatus back and forward, its ends resting on the railings. The sheet (r.) to be printed is placed upon the registering board (S) its upper edge corresponding with the upper edge of the board, and the clamps are placed upon the well-tilted end (t) with their end against the mouth pin (u.), so as when sheet to clasp the paper in the right place the clamps are then sheet, clasping one end of the paper and by means of the pointed notching holes for registering the second side of the sheet. The sheet is then

carried by the clamp to the press. The book and thence over the friction bar (a) or roller (c) and the clamp to the rear until their place being guided by slot and peg. The combination of roller (c) is then moved forward and give the impression. For a further illustration of these improvements, I refer to the annexed drawings and to the model, deposited in the Patent office. The invention here claimed and desired to be secured by Letters Patent, is the above described apparatus, for making, retaining or placing the sheet and giving the impression in printing. Particulars clearly the arrangement and combination of the parts and their application to commercial or ornamental articles of furniture.
